UNITED STATES PATENT OFFICE.

LEONIDAS G. WOOLLEY, OF KENTON, OHIO, ASSIGNOR TO THE NATIONAL MAGNETO ELECTRIC TELEGRAPH COMPANY, OF SPRINGFIELD, OHIO.

FIRE-ALARM-TELEGRAPH BOX.

SPECIFICATION forming part of Letters Patent No. 664,366, dated December 18, 1900.

Application filed December 28, 1899. Serial No. 741,813. (No model.)

To all whom it may concern:

Be it known that I, LEONIDAS G. WOOLLEY, a citizen of the United States, residing at Kenton, in the county of Hardin and State of Ohio, have invented certain new and useful Improvements in Fire-Alarm-Telegraph Boxes; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to an improvement in fire-alarm-telegraph boxes; and its object is to do away with the use of the usual batteries or constant source of electrical energy and to substitute therefor a magneto-electric telegraph for sending impulses from each box to headquarters, so as to give the number of the box, and thus locate the neighborhood of the fire.

My invention consists in a magneto-electric machine or generator of the usual type, a pivoted spring-actuated yoke provided with internal shoulders upon opposite sides and which regulate the turning of the armature, and a connecting-link extending upwardly from the yoke and having its upper end pivoted to a lever, which engages with a toothed wheel provided with projections upon its periphery and which are arranged in such relation to each other that they give the number of the box, combined with a mechanism for operating the said toothed wheel and which mechanism is set in motion either by a key or any other releasing mechanism that may be preferred.

It still further consists in a magneto-electric machine or generator, a spring-actuated pivoted yoke for manipulating the same, and a connecting-link which extends upwardly from the yoke, combined with a lever, to which the upper end of the link is pivoted, and a spring-actuated wheel having projections upon its periphery, the lever and the yoke being operated by the same spring, as will be more fully described hereinafter.

In the accompanying drawings, Figure 1 is a side elevation of a mechanism for a fire-

alarm box. Fig. 2 is an end view of the same. Fig. 3 represents a perspective of the yoke and the lever, showing them connected. Fig. 4 is a plan view of my apparatus complete. 55 Fig. 5 is a horizontal section taken through the magneto-electric machine just above the armature. Fig. 6 is a perspective of the slide D' and its attachments.

represents the base-plate, to which a suitable frame B is secured. Secured upon this base in any suitable manner are any suitable number of permanent horseshoe-magnets C, according to the capacity of the machine required, and which magnets have applied to 60 their outer sides the connecting-plates D, through which the screws E are passed in between the magnets and which screws take into the pole-pieces F, which are placed in direct contact with the magnets and which 65 form the frame G, which is placed inside of the poles of the magnets C and is secured to the base A, as shown. The revolving armature H is journaled in end pieces which 70 connect the pole-pieces F and is of the ordinary 75 construction. Upon the inner end of the shaft of this armature are secured both the pinion I and lug J, which revolves with the armature and which operates in connection with the pivoted yoke K for the purpose of 80 manipulating the armature. Upon the inner opposite sides of the yoke K are formed shoulders L, against which the lug J alternately strikes as the yoke is manipulated either through the key M or in any other way that 85 may be preferred. These shoulders L are so arranged that when the yoke is depressed the outer end of the lug J slips off from the shoulder behind which it was catching and after 90 being carried around half a circle by the armature the end of the lug catches against the other shoulder L, and thus prevents the armature from revolving further until the yoke is again manipulated. When the yoke is depressed, the lug is released from the lower 95 shoulder and catches on the upper one. Then when the yoke rises the lug is released from the upper shoulder and again catches on the lower one. This armature is caused to 100 revolve by means of the large wheel N, which is secured to the spring-drum O, provided with teeth upon its outer periphery, and

which drum each time the yoke is manipulated causes the armature to make half a revolution. By manipulating the yoke either through the key M or in any other way the 5 armature may be made to revolve so as to give any number of electrical impulses, so as to transmit the number of the box.

Upon the shaft P of the drum O, outside of the drum, is secured a ratchet Q, with which 10 the pawl R engages for the purpose of preventing the spring from unwinding and with which ratchet also engages a second spring-actuated pawl S upon the lower end of the winding-lever T, and which lever is pivoted 15 at its lower end upon the shaft P. After this lever T has been used in the usual manner to wind the spring in the drum O the lever T is turned up into the position shown in Fig. 2 and held out of the way by means of the 20 catch U; which engages with a pin on the side of the lever, as shown.

Pivoted to the outer upper corner of the yoke K is a rigid connecting-link V, which is pivoted at its upper end to the lever W, pivoted 25 at its outer end to one of the upper corners of the frame B, and which lever has a V-shaped projection X upon its inner end to engage with the wheel Y, provided with projections upon its periphery to indicate the 30 number of the box. Secured to the base at any suitable point is a spring Z, which bears upon the outer lower corner of the yoke K, and thus causes the yoke to be forced upward, and the lever W has its projection X 35 forced upwardly against the wheel Y through the rigid connecting-link V, which connects the yoke and the inner end of the lever. Thus by a single spring I make the yoke and the lever W automatic in their action, and when 40 the lever W is manipulated by the wheel Y the yoke K is operated at the same time, so as to allow the armature to make half-revolutions, and thus send impulses to headquarters, so as to give the number of the box being 45 operated. The wheel Y is provided with projections upon its periphery, as shown, and which projections are arranged according to the number of the box, and these projections passing over the projection X upon the end 50 of the lever W operate the yoke K and allow the armature to revolve. This wheel Y is operated by a spring A', having one end secured to the shaft C', upon which the wheel Y is placed, and to the opposite end of the 55 shaft from the wheel is connected a train of gears B', which forms a step-by-step escapement for controlling the speed at which the wheel Y shall revolve in sending in the number of the box when an alarm is given.

60 Extending across the top of the frame B is the endwise-moving slide D', which has the spring E' connected to one end, so as to cause the slide to move outwardly whenever it is left free to move by the endwise movement 65 of the slide F', which is manipulated by a key G', and which key causes the slide F' to move sufficiently far endwise that its end H',

which catches over the end of the slide D', is withdrawn, as shown in Figs. 1 and 2, to allow the slide D' to be forced outwardly the 70 full length of its movement by the spring E'. Secured to this slide D' and projecting upwardly is the post I', which moves with the slide, and from the top of which post projects the horizontal arm or catch J', which 75 catches under the end of the vibrating arm K' of the escapement. As long as the slide F' is forced backwardly, as shown in Fig. 1, this post I' and its arm J' are moved backward sufficiently far to prevent the vibrator 80 K' from engaging therewith, and hence the spring A' will cause the wheel Y to make a full revolution and thus send the number of the box to headquarters the number of times the group of projections upon its surface are 85 repeated. As here shown, there are five sets of these projections, and the number of the box is transmitted five times to headquarters. After the wheel has revolved its full distance the projecting pin L' comes in contact with 90 the stationary stop M', projecting upwardly from the top of the frame B. Each time the box is operated the chief or some one in charge must open the box and through the thumb-wheel N', secured to the wheel Y, turn 95 the wheel entirely around, ready to be operated again.

This invention differs from the devices now in use only in having the wheel Y under the tension of the spring A', so that each time 100 the box is operated the wheel revolves once, and the spring must then be wound up again before the wheel can be made to make another revolution.

As shown, the key G' has its operating part 105 which engages with the slide F' bent so that after the slide F' has been forced backward into the position shown in Fig. 1 the key cannot be released until the chief or one who has the box in charge comes and opens the door, 110 when the key is withdrawn on the opening of the door. Connected to this slide F' is a spring O', (shown in Fig. 2,) which when the end of the slide D' is forced backward by the chief causes the slide F' to spring back 115 into its normal position, with its end H' across the end of the slide D' for the purpose of preventing the escapement from operating and allowing the spring A' to unwind and the wheel Y to revolve. 120

Besides doing away with the use of batteries or other constant source of electrical energy by using the magneto-electric machine, a great saving in the cost of batteries or other electromotive power is effected and 125 I am enabled to use much lighter conducting-wire than can be used in connection with a battery. The batteries being of a low tension, a heavy conducting-wire is necessary, and this wire is liable to be broken down by sleet 130 or ice or by violent winds, which is not the case where a steel wire of No. 14 or No. 16 gage is used, which I find to be amply sufficient.

Having thus described my invention, I claim—

1. In a fire-alarm-telegraph system, a magneto-electric machine, a yoke for manipulating the same, and a motor for revolving the armature, combined with a second motor having an escapement, a wheel operated by the second motor, and provided with projections upon its periphery, and a lever operated by said wheel, and which is connected with the yoke, substantially as shown.

2. In a fire-alarm-telegraph system, a magneto-electric machine, a revolving armature, and a motor for revolving said armature when it is left free to revolve, combined with a spring-actuated yoke for manipulating the armature, a lever provided with a projection, the lever and the yoke being connected so as to move simultaneously, a wheel provided with teeth upon its periphery, and which teeth operate said lever and yoke, a spring for causing the wheel to revolve, and an escapement for regulating the rapidity with which the wheel shall revolve, substantially as described.

3. In a fire-alarm-telegraph system, a magneto-electric machine provided with a revolving armature, and a motor for revolving said armature when left free to move, combined with a yoke for manipulating said armature, and a lever connected to the yoke so that the

two will move simultaneously, and a spring-actuated wheel provided with means upon its surface for operating said lever and yoke when the wheel is allowed to revolve, substantially as set forth.

4. In a fire-alarm-telegraph system, a magneto-electric machine, a mechanism for revolving the armature when it is left free to move, and a lug secured to the shaft of the armature, and revolving therewith, combined with a spring-actuated yoke, provided with shoulders upon its opposite sides against which the lug alternately catches, a rigid connection loosely pivoted to the yoke, a pivoted lever provided with a projection at its inner end, and to which the rigid connection is also pivoted, and a spring-actuated revolving wheel provided with projections upon its periphery to simultaneously operate the lever and the yoke so that as each projection upon the periphery of the wheel comes in contact with the projection upon the lever the lever and yoke will both be depressed and allow the armature to make a half-revolution, substantially as specified.

In testimony whereof I affix my signature in presence of two witnesses.

LEONIDAS G. WOOLLEY.
